MOUNTING FOR HAND TELEPHONES

Hans Sengebusch, Villa Park, Ill., assignor to
Associated Electric Laboratories, Inc., Chicago,
Ill., a corporation of Delaware

Application April 14, 1939, Serial No. 267,816

5 Claims. (Cl. 179—146)

The present invention relates to mountings for telephones and, more particularly, to desk mountings for hand telephones.

A mounting of this type conventionally comprises a supporting base, a pedestal carrying a calling dial, and a cradle provided with a switch-hook and adapted to support a hand telephone or hand set of the well-known Monophone type; the usual substation apparatus, including an induction coil, a condenser, a signal bell and a switching mechanism, being housed in the supporting base and pedestal of the mounting.

It is an object of the present invention to provide a mounting of the type described which is of simple and rugged construction and which embodies an improved arrangement for facilitating movement from place to place of the mounting and the hand telephone supported thereby.

The object set forth above is attained in accordance with the present invention by providing a mounting of the character described comprising a base, a pedestal and a cradle including two spaced-apart and upwardly extending cradle members, the cradle members being provided with aligned cradle seats therein adapted to support the handle of the hand telephone. The pedestal includes front and rear upwardly and inwardly extending walls and upwardly extending side walls formed by the cradle members. The rear wall of the pedestal and the cradle members are so constructed and arranged that a substantially channel-shaped recess is provided in the rear of the pedestal, the recess provided in the rear of the pedestal extending below the plane of the aligned cradle seats provided in the cradle members. A movable element is carried by the mounting which has two spaced-apart handle portions, the element having a normal position wherein the two spaced-apart handle portions thereof are disposed substantially entirely in the recess provided in the rear of the pedestal and an operated position wherein the two spaced-apart handle portions thereof are disposed substantially out of the recess provided in the rear of the pedestal. The element is so constructed and arranged that the two spaced-apart handle portions thereof are adapted to be positioned on opposite sides of the handle of the hand telephone when the element occupies its operated position, thereby to facilitate movement from place to place of the mounting and the hand telephone supported thereby and to prevent displacement of the handle of the hand telephone from the aligned cradle seats provided in the cradle members.

The novel features believed to be characteristic of the invention are set forth with particularity in the appended claims. The invention, both as to its organization and method of operation, together with further objects and advantages thereof, will best be understood by reference to the

following specification taken in connection with the accompanying drawing, in which Figure 1 is a perspective view of a mounting for a hand telephone which is constructed and arranged in accordance with the present invention; Fig. 2 is a fragmentary longitudinal sectional view of the mounting shown in Fig. 1 and a hand telephone supported thereby, illustrating the normal positions of certain elements of the mounting; and Fig. 3 is a longitudinal sectional view of the mounting shown in Fig. 1 and the hand telephone supported thereby, illustrating the operated positions of the elements of the mounting and the substation apparatus housed therein.

Referring now more particularly to Figs. 1 and 3 of the drawing, there is shown a desk mounting or support 10 for a hand telephone or hand set of the well-known Monophone type illustrated at 11, which mounting comprises a supporting base 12, a pedestal 13, and a cradle 14 including two spaced-apart and upwardly extending cradle members 15 and 16. The pedestal 13 is provided with front and rear upwardly and inwardly extending walls 17 and 18 converging slightly forwardly of the cradle 14, a top wall 19 extending between the front and rear walls 17 and 18, respectively, and upwardly extending side walls formed by the cradle members 15 and 16. The top and rear walls 19 and 18, respectively, of the pedestal 13 and the cradle members 15 and 16 are so constructed and arranged that a continuous substantially channel-shaped recess 20 is provided in the top and rear of the pedestal 13. Aligned cradle seats 21 and 22 are provided in the cradle members 15 and 16, respectively, the cradle seat 21 provided in the cradle member 15 being formed therein by spaced-apart and upwardly extending front and rear tines 23 and 24, respectively; and the cradle seat 22 provided in the cradle member 16 being formed therein by spaced-apart and upwardly extending front and rear tines 25 and 26, respectively. The cradle seats 21 and 22 provided in the cradle members 15 and 16 are provided with recesses therein into which two metal inserts 27 and 28, respectively, are securely positioned, the inserts 27 and 28 having openings therein into which two switchhooks or plungers 29 and 30, respectively, are slidably mounted.

The front wall 17 of the pedestal 13 is provided with an annular recess 17a therein within which a calling dial 31 is positioned and supported in place. The interiors of the supporting base 12 and the pedestal 13 are hollow in order to provide a continuous cavity 32 therein which accommodates the usual substation apparatus, such as a signal bell 33, an induction coil 34, a condenser 35 and a switching mechanism 36, the switching mechanism 36 being operatively associated with the switchhooks or plungers 29 and 30 by a suitable connecting lever mechanism 37. The open-

ing into the cavity 32 formed in the supporting base 12 and the pedestal 13 is closed by a suitable base plate 38 fastened to the supporting base 12. Also, the mounting 10 is so constructed and arranged that the center of gravity thereof is disposed in a substantially vertical plane extending through the aligned cradle seats 21 and 22 provided in the cradle members 15 and 16, respectively, in order to insure proper balance of the 10 mounting.

The handle of the hand telephone 11 is supported in the aligned cradle seats 21 and 22 provided in the cradle members 15 and 16, respectively, the weight of the hand telephone being 15 adequate to retain the switchhooks or plungers 29 and 30 in their depressed positions against the bias of the switching mechanism 36, in order to retain the switching mechanism 36 in its open circuit position in a well-known manner. When 20 the handle of the hand telephone 11 is removed from the supporting cradle seats 21 and 22 provided in the cradle members 15 and 16, respectively, the switchhooks or plungers 29 and 30 are projected outwardly under the bias of the switching mechanism 36, in order to cause the switching mechanism 36 to be operated to its closed circuit position in a well-known manner.

In order to facilitate movement of the mounting 10 and the hand telephone 11 supported 30 thereby from place to place, an arrangement is provided which comprises a substantially channel-shaped plate 39 having a rear wall 40 extending between the cradle members 15 and 16 and two inwardly flanged side walls 41 and 42 disposed in abutting engagement with the cradle members 15 and 16, respectively. The plate 39 is arranged substantially entirely in the recess 20 provided in the rear of the pedestal 13 and is rigidly secured in place by two screws 43 and 44 extending through openings provided in the rear wall 40 of the plate 39 and threaded into tapped holes provided in the rear wall 18 of the pedestal 13. Slidably mounted on the rear wall 40 of the plate 39 is a substantially V-shaped element 45 having two spaced-apart pieces 46 and 47 provided with handle portions 48 and 49, respectively. More particularly, the pieces 46 and 47 of the element 45 are secured together adjacent the lower ends thereof by rivets 50 extending 50 therebetween. The piece 41 of the element 45 is provided with an elongated slot 51 therein which slidably receives a rivet 52 rigidly carried by the rear wall 40 of the plate 39.

The rear wall 18 of the pedestal 13, the rear 55 wall 40 of the plate 39, and the cradle members 15 and 16 are so constructed and arranged that a cavity 53 is defined thereby in the rear of the pedestal 13, which cavity extends below the plane of the aligned cradle seats 21 and 22 provided in the cradle members 15 and 16, respectively; and the element 45 is disposed in the cavity 53, the element 45 being slidably supported by the rear wall 40 of the plate 39 as previously explained. As best shown in Fig. 2, the element 45 has a normal position wherein the two spaced-apart handle portions 48 and 49 of the pieces 46 and 47, respectively, thereof are disposed substantially entirely in the cavity 53 provided in the rear of the pedestal 13; and, as best shown 65 in Fig. 3, the element 45 has an operated position wherein the two spaced-apart handle portions 48 and 49 of the pieces 46 and 47, respectively, thereof are disposed substantially out of the cavity 53 provided in the rear of the pedestal 13. The element 45 is so constructed and ar-

ranged that the handle portion 49 of the piece 47 thereof is readily accessible when the element 45 occupies its normal position, and that the two spaced-apart handle portions 48 and 49 of the pieces 46 and 47, respectively, thereof are 5 positioned on opposite sides of the handle of the hand telephone 11 when the element 45 occupies its operated position, thereby to facilitate movement from place to place of the mounting 10 and the hand telephone 11 supported thereby. 10

It is contemplated that a person wishing to move the mounting 10 and the hand telephone 11 supported thereby from one place to another will seize the handle portion 49 of the piece 47 of the element 45 and exert a lifting force thereon, thereby to cause the element 45 to be slidably moved from its normal position to its operated position. When the element 45 is moved to its operated position, the handle portion 48 of the piece 46 thereof will be seized by the thumb 20 of the person, thereby to provide a convenient composite handle for moving the mounting 10 and the hand telephone 11 supported thereby from one place to another. Also, it is noted that the handle portions 48 and 49 of the pieces 46 25 and 47, respectively, of the element 45 are disposed on opposite sides of the handle of the hand telephone 11 when the element 45 occupies its operated position, thereby to prevent displacement of the handle of the hand telephone 11 30 from the aligned cradle seats 21 and 22 provided in the cradle members 15 and 16, respectively, incident to the movement of the mounting 10 and the hand telephone 11 supported thereby from one place to another. 35

In view of the foregoing, it is apparent that a desk mounting for a hand telephone is provided which is of simple and rugged construction and which embodies an improved arrangement for facilitating movement from place to 40 place of the mounting and the hand telephone supported thereby.

While there has been described what is at present considered to be the preferred embodiment of the invention, it will be understood that various modifications may be made therein, and it is contemplated in the appended claims to cover all such modifications as fall within the true spirit and scope of the invention.

What is claimed is:

1. A mounting for a hand telephone comprising a base, a pedestal, a cradle provided with a cradle seat therein adapted to support the handle of the hand telephone, said pedestal having an opening provided therein disposed below the plane 55 of the cradle seat provided in said cradle, and a movable element carried by said mounting and having two spaced-apart handle portions, said element having a normal position wherein the two spaced-apart handle portions thereof are disposed substantially entirely in the opening provided in said pedestal and an operated position wherein the two spaced-apart handle portions thereof are disposed substantially out of the opening provided in said pedestal, said element 60 being so constructed and arranged that the two spaced-apart handle portions thereof are adapted to be positioned on opposite sides of the handle of the hand telephone when the element occupies its operated position, thereby to facilitate movement from place to place of said mounting and the hand telephone supported thereby and to prevent displacement of the handle of the hand telephone from the cradle seat provided in said cradle. 65

2. A mounting for a hand telephone, comprising a base, a pedestal, a cradle including two spaced-apart and upwardly extending cradle members, said cradle members being provided with aligned cradle seats therein adapted to support the handle of the hand telephone, said pedestal including front and rear upwardly and inwardly extending walls and side walls formed by said cradle members, the rear wall of said pedestal and said cradle members being so constructed and arranged that a substantially channel-shaped opening is provided in the rear of said pedestal, the opening provided in the rear of said pedestal extending below the plane of the aligned cradle seats provided in said cradle members, and a movable element carried by said mounting and having two spaced-apart handle portions, said element having a normal position wherein the two spaced-apart handle portions thereof are disposed substantially entirely in the opening provided in the rear of said pedestal and an operated position wherein the two spaced-apart handle portions thereof are disposed substantially out of the opening provided in the rear of said pedestal, said element being so constructed and arranged that the two spaced-apart handle portions thereof are adapted to be positioned on opposite sides of the handle of the hand telephone when the element occupies its operated position, thereby to facilitate movement from place to place of said mounting and the hand telephone supported thereby and to prevent displacement of the handle of the hand telephone from the aligned cradle seats provided in said cradle members.

3. A mounting for a hand telephone, comprising a base, a pedestal, a cradle including two spaced-apart and upwardly extending cradle members, said cradle members being provided with aligned cradle seats therein adapted to support the handle of the hand telephone, said pedestal including front and rear upwardly and inwardly extending walls and side walls formed by said cradle members, the rear wall of said pedestal and said cradle members being so constructed and arranged that a substantially channel-shaped opening is provided in the rear of said pedestal, the opening provided in the rear of said pedestal extending below the plane of the aligned cradle seats provided in said cradle members, and a substantially V-shaped element slidably supported on said mounting and having two spaced-apart handle portions, said element having a normal position wherein the two spaced-apart handle portions thereof are disposed substantially entirely in the opening provided in the rear of said pedestal and an operated position wherein the two spaced-apart handle portions thereof are disposed substantially out of the opening provided in the rear of said pedestal, said element being so constructed and arranged that the two spaced-apart handle portions thereof are adapted to be positioned on opposite sides of the handle of the hand telephone when the element occupies its operated position, thereby to facilitate movement from place to place of said mounting and the hand telephone supported thereby and to prevent displacement of the handle of the hand telephone from the aligned cradle seats provided in said cradle members.

4. A mounting for a hand telephone, comprising a base, a pedestal, a cradle including two

spaced-apart and upwardly extending cradle members, said cradle members being provided with aligned cradle seats therein adapted to support the handle of the hand telephone, said pedestal including front and rear upwardly and inwardly extending walls and side walls formed by said cradle members, the rear wall of said pedestal and said cradle members being so constructed and arranged that a substantially channel-shaped opening is provided in the rear of said pedestal, the opening provided in the rear of said pedestal extending below the plane of the aligned cradle seats provided in said cradle members, a member extending between said cradle members and carried thereby, and an element slidably carried by said last-mentioned member and having two spaced-apart handle portions, said element having a normal position wherein the two spaced-apart handle portions thereof are disposed substantially entirely in the opening provided in the rear of said pedestal and an operated position wherein the two spaced-apart handle portions thereof are disposed substantially out of the opening provided in the rear of said pedestal, said element being so constructed and arranged that the two spaced-apart handle portions thereof are adapted to be positioned on opposite sides of the handle of the hand telephone when the element occupies its operated position, thereby to facilitate movement from place to place of said mounting and the hand telephone supported thereby and to prevent displacement of the handle of the hand telephone from the aligned cradle seats provided in said cradle members.

5. A mounting for a hand telephone, comprising a base, a pedestal, a cradle including two spaced-apart and upwardly extending cradle members, said cradle members being provided with aligned cradle seats therein adapted to support the handle of the hand telephone, said pedestal including front and rear upwardly and inwardly extending walls and side walls formed by said cradle members, a plate carried by said mounting and extending between said cradle members, the rear wall of said pedestal, said plate and said cradle members being so constructed and arranged that an opening is defined thereby in the rear of said pedestal, the opening provided in the rear of said pedestal extending below the plane of the aligned cradle seats provided in said cradle members, and an element slidably carried by said plate and having two spaced-apart handle portions, said element having a normal position wherein the two spaced-apart handle portions thereof are disposed substantially entirely in the opening provided in the rear of said pedestal and an operated position wherein the two spaced-apart handle portions thereof are disposed substantially out of the opening provided in the rear of said pedestal, said element being so constructed and arranged that the two spaced-apart handle portions thereof are adapted to be positioned on opposite sides of the handle of the hand telephone when the element occupies its operated position, thereby to facilitate movement from place to place of said mounting and the hand telephone supported thereby and to prevent displacement of the handle of the hand telephone from the aligned cradle seats provided in said cradle members.
